UNITED STATES PATENT OFFICE.

ADOLPH C. RECKER, OF OAKVILLE, CONNECTICUT, ASSIGNOR TO WATERBURY MFG. CO., OF WATERBURY, CONNECTICUT, A CORPORATION.

SOCKET FOR INCANDESCENT ELECTRIC LAMPS.

1,104,931.

Specification of Letters Patent. Patented July 28, 1914.

Application filed October 27, 1913. Serial No. 797,522.

To all whom it may concern:

Be it known that I, ADOLPH C. RECKER, a citizen of the United States, residing at Oakville, in the county of Litchfield and State of Connecticut, have invented a new and useful Improvement in Sockets for Incandescent Electric Lamps; and I do hereby declare the following, when taken in connection with the accompanying drawings and the characters of reference marked thereon, to be a full, clear, and exact description of the same, and which said drawings constitute part of this application, and represent, in—

15 Figure 1 a side view of an incandescent electric lamp socket constructed in accordance with my invention. Fig. 2 a view at right angles to Fig. 1, with the upper end of the socket in section. Fig. 3 a view similar to Fig. 2, illustrating a modified form of my invention.

20 This invention relates to an improvement in sockets for incandescent electric lamps, and particularly to sockets which are provided with an eye adapted to be connected with the end of the chain in suspension fixtures. In the more general construction of these sockets, these eyes or loops are formed from cast metal and provided with a screw 30 threaded hollow stem adapted to be screwed into a turned metal neck which is connected with the cap of the socket.

The object of this invention is to form the neck of the socket from sheet metal and 35 connect an eye or loop directly with the neck, thus simplifying the construction and reducing the cost of manufacture; and the invention consists in the construction herein-after described and particularly recited in 40 the claims.

In carrying out my invention, I form the neck 2 from sheet metal either integral with the cap 3 of an ordinary socket 4, as shown in Fig. 2 of the drawings, or separate therefrom and connected with the cap as shown in Fig. 3 of the drawings. This neck being

drawn from sheet metal has its outer end turned inward, forming a downwardly extending internal flange 5, and in opposite sides of the neck are perforations 6 and 7 50 to receive the ends 9 and 8 of a ring or loop 10 which may be connected with a chain fixture. The internal flange 5 is somewhat smaller in diameter than the diameter of the neck itself so as to leave an annular space 55 between them, and this space provides for the entrance to a sufficient degree of the ends of the ring to firmly connect the ring with the neck, and furthermore, the flange so nearly covers the ends of the ring that electric wires passing into the socket will not be frayed by the ends of the ring, and the internal flange provides a smooth surface facilitating the entrance of the wires into the socket. 65

I claim:

1. A socket for incandescent electric lamps having a sheet metal neck formed on opposite sides with openings and provided with an integral inwardly extending flange 70 forming an opening through the neck, said flange extending beyond the upper edge of the said openings, and a split ring the ends of which are inserted into said openings.

2. A socket having a neck formed integral 75 with the cap, said neck formed with openings on opposite sides and with an integral, inwardly extending flange smaller in diameter than the diameter of the neck forming an opening through the neck, the lower 80 edge of the said flange extending beyond the upper edge of the said openings, and a ring the ends of which are inserted into said openings.

In testimony whereof, I have signed this 85 specification in the presence of two subscribing witnesses.

ADOLPH C. RECKER.
